US00D981184S

(12) **United States Design Patent** (10) **Patent No.:** **US D981,184 S**
LaMance (45) **Date of Patent:** **** Mar. 21, 2023**

(54) **INSULATED BEVERAGE CONTAINER**

(71) Applicant: **Kanga, LLC.**, Greenville, SC (US)

(72) Inventor: **Logan T. LaMance**, Greenville, SC (US)

(73) Assignee: **Kanga, LLC**, Greenville, SC (US)

(**) Term: **15 Years**

(21) Appl. No.: **29/762,423**

(22) Filed: **Dec. 16, 2020**

(51) LOC (14) Cl. **07-99**

(52) U.S. Cl.

USPC **D7/607**

(58) **Field of Classification Search**

CLAIM

The ornamental design for an insulated beverage container, as shown and described.

DESCRIPTION

FIG. 1 is a perspective view of the insulated beverage container;

FIG. 2 is a front side view of the insulated beverage container;

FIG. 3 is a rear side view of the insulated beverage container;

FIG. 4 is a left side view of the insulated beverage container;

FIG. 5 is a right side view of the insulated beverage container;

FIG. 6 is a top view of the insulated beverage container; and, FIG. 7 is a bottom view of the insulated beverage container. The broken lines are for showing stitching, zipper tabs and logo placement of the insulated beverage container and form no part of the claimed design.
